FILTER ATTACHMENT FOR SPARK PLUGS

Myron J. Weiner, Los Angeles, Calif., assignor to Hallett
Manufacturing Company, Los Angeles, Calif., a corporation of California

Filed May 24, 1966, Ser. No. 2,417

Term of patent 14 years

(Cl. D26—1)

FIG. 2.

FIG. 3.

FIG. 1.

FIG. 1 is a side elevation of a filter attachment for spark plugs showing my new design;

FIG. 2 is a top plan view thereof; and
FIG. 3 is a bottom plan view thereof.

I claim:

The ornamental design for a filter attachment for spark plugs, as shown.
